UNITED STATES PATENT OFFICE

THOMAS E. SINCLAIR, OF ST. PAUL, MINNESOTA

PORTABLE MOTOR-DRIVEN HACK SAW

Application filed September 2, 1927. Serial No. 217,210.

This invention relates to a motor driven hack saw, the general object of the invention being to provide a device of this nature which can be easily transported from place to place and which can be operated by a small motor using ordinary current, with means for breaking the circuit of the motor as soon as the blade cuts through the work piece, such means also holding the circuit open when the 10 hack saw is in a lowered position.

Another object of the invention is to provide means at the front end of the device for controlling clutch means on the driven shaft so that the operator can easily throw 15 the saw out of operation without stopping the motor, as he stands in front of the device.

A still further object of the invention is to so arrange the parts that the device will need but little attention on the part of the operator after the device starts to actuate. 20

This invention also consists in certain other features of construction and in the combination and arrangement of the several parts, to be hereinafter fully described, illustrated 25 in the accompanying drawings and specifically pointed out in the appended claims.

In describing my invention in detail, reference will be had to the accompanying drawings wherein like characters denote like or 30 corresponding parts throughout the several views, and in which:—

Figure 1 is an elevation looking toward one side of the device.

Figure 2 is a similar view of the opposite 35 side thereof.

Figure 3 is a plan view.

Figure 4 is a view of one end of the device.

Figure 5 is a view of the opposite end 40 thereof.

Figure 6 is a section on line 6—6 of Figure 3.

Figure 7 is a diagrammatic view of the circuit.

In these views, 1 indicates a table or frame 45 which supports the small frame 2 and the support 3 for the clamp 4 which holds the work piece A in position, the handle 5 of the clamp extending to a point in front of the table. Shafts 6 and 7 are journaled in the frame 2 and the shaft 6 carries a pulley 8

and a pinion 9, the pinion 9 meshing with a gear 10 rotatably mounted on the shaft 7 and having a clutch part for engaging a sliding clutch part 11 keyed to the shaft 6, this latter part being moved into operative and inoperative position through means of a clutch fork 11' to which is connected a bell crank 12 pivoted to the under side of the table and to the outer end of which is pivoted a rod 13 which extends under the table and has its 60 outer end extending beyond the front end of the table so that an operator standing at the front end of the device can shift the clutch by moving the rod.

A motor M is arranged under the table and 65 is supported on a shelf carried by the table and a belt 14 passes over a pulley on the motor shaft and over the pulley 8 so that the shaft 6 will be driven from the motor.

A guiding member 15 is pivotally supported 70 by the frame 2 by having its depending ear 16, arranged at the rear end of the member 15, pivoted to a part of the frame. A bar 17 is slidably supported in the member 15 and the hack saw frame 18 is fastened to this 75 bar. The blade of the saw is shown at 19. A crank 20 is secured to one end of the shaft 7 and a pitman 21 connects the crank with the frame 18 so that the rotary movement of the shaft 7 is transmitted to the hack saw 80 frame to impart a reciprocatory motion to the frame.

A lever 22 is pivotally supported on the table and carries a switch 23 for bridging a 85 pair of contacts 24 arranged in the circuit A of the motor M. The switch is normally held in closed position by means of a spring 25 engaging a lever and an adjustable post 26 is carried by the lever and is arranged under the member 15 so that when said member drops, it will strike said post and thus tilt the lever and move the switch 23 off the contacts 24 and thus break the circuit of the motor. The circuit is provided with a hand 90 operated switch B.

From the foregoing it will be seen that when the motor is in operation, the shaft 6 will be driven and this movement will be imparted to the gear 10 and if the clutch 95 is in operative position, the shaft 7 will also 100

be driven so that the hack saw will be reciprocated by the rotary movement of the crank, the saw being guided in its movement by the member 15. If, for any reason, the 5 operator wishes to stop the action of the saw, he would simply shift the clutch by means of the rod 13 so as to stop the rotary movement of the shaft 7. When the saw cuts through the work piece, the downward movement 10 of the parts will break the circuit to the motor and this circuit will also be broken when the saw is in its lowest position. By providing the clamp for the work piece and the means for automatically stopping the 15 device when the saw has passed through the work piece, the operator, after starting the saw into operation, can leave, as the device will need no further action as it will stop itself as soon as the saw passes through the 20 work piece. As will be seen, the device is small enough to enable it to be transported from place to place as desired.

It is thought from the foregoing description that the advantages and novel features 25 of my invention will be readily apparent.

I desire it to be understood that I may make changes in the construction and in the combination and arrangement of the several parts, provided that such changes fall within 30 the scope of the appended claim.

What I claim is:—

A portable motor driven hack saw comprising 35 a table adapted to support a light weight electric motor to be connected to an electric source, a work holder on said table, a support on the table, a power shaft journaled to said support and driven by the motor, a driven shaft carried by the support, a means for connecting said shafts, a crank at one end of the 40 driven shaft, a pitman connected to said crank and to the frame of a hack saw for cutting material supported by the work holder, a guide sleeve having one end pivoted to the support and its other end free to move 45 upwardly and downwardly with respect to the work holder, a guide member slidable in said sleeve and connected to the frame of the hack saw, contacts carried by the table under the free end of the sleeve and in circuit with 50 the motor and electrical source, and a spring pressed and pivotally mounted contact arm carried by the table and adapted to normally bridge the contacts to complete the circuit to the motor and to be engaged and moved 55 by the guide sleeve to disengage the contact and break the circuit to the motor when the hack saw passes completely through the material on the work holder.

In testimony whereof I affix my signature.

60 THOMAS E. SINCLAIR.
